United States Patent Office

Des. 208,121
Patented July 18, 1967

208,121

REFLECTING TRAFFIC GUIDE OR SIMILAR ARTICLE

John B. Keats, Marietta, Ohio, assignor to Borg-Warner
Corporation, a corporation of Illinois

Filed May 31, 1966, Ser. No. 2,469

Term of patent 14 years

(Cl. D72—1)

FIG. 1

FIG. 2

FIGURE 1 is a top plan view of a reflecting traffic guide or similar article showing my new design, and
FIGURE 2 is a front elevation thereof.

I claim:

The ornamental design for a reflecting traffic guide or similar article, substantially as shown.
